OTHER PUBLICATIONS

U.S. Appl. No. 29/410,486, entitled "Human Model," filed Jan. 9, 2012.

Primary Examiner — Mary Ann Calabrese(74) *Attorney, Agent, or Firm* — SAIDMAN DesignLaw Group(57) **CLAIM**

The ornamental design for a human model, as shown and described.

DESCRIPTION

FIG. 1 is a front view of a human model showing our new design;

FIG. 2 is a side perspective view thereof;

FIG. 3 is a front perspective view thereof; and,

FIG. 4 is an alternative front perspective view thereof. The broken lines illustrate environmental structure and form no part of the claimed design.
